Primary Examiner — Kimberly Barnes(74) *Attorney, Agent, or Firm* — Bryce D. Miracle(57) **CLAIM**

The ornamental design for a full metal jersey, substantially as shown and described.

DESCRIPTION

FIG. 1 is a front perspective view of a full metal jersey showing the new design;

FIG. 2 is a front view thereof;

FIG. 3 is a rear view thereof;

FIG. 4 is a left side view thereof;

FIG. 5 is right side view thereof;

FIG. 6 is a top view thereof; and,

FIG. 7 is a bottom view thereof.

The broken lines in the drawings depict portions of the full metal jersey that form no part of the claimed design.

1 Claim, 5 Drawing Sheets(56)
